Primary Examiner — Eric Goodman*Assistant Examiner* — Ryan Harvey(74) *Attorney, Agent, or Firm* — Clark IP Law, PLC(57) **CLAIM**

The ornamental design for an LED light fixture, as shown and described.

DESCRIPTION

FIG. 1 is a right elevational side view, the opposite side being a mirror image thereof;

FIG. 2 is a top plan view thereof;

FIG. 3 is a bottom plan view thereof;

FIG. 4 is a front elevational view of an LED light fixture; the opposite side being a mirror image thereof;

FIG. 5 is a top isometric view thereof; and,

FIG. 6 is a bottom isometric view thereof.

1 Claim, 4 Drawing Sheets(56)
